United States Patent

Des. 240,544
Patented July 13, 1976

240,544

MINIATURE TRAMWAY CAR AND PLATFORM THEREFOR

Harold J. Howard, P.O. Box 914, Dillon, Colo. 80435

Filed June 24, 1974, Ser. No. 482,758

Term of patent 14 years

Int. Cl. D21—01

U.S. Cl. D34—15 MM

FIG. 5FIG. 6FIG. 7

FIG. 1 is a perspective view of a miniature tramway car and platform therefor showing my new design;

FIG. 2 is a right end elevational view thereof;

FIG. 3 is a left end elevational view thereof;

FIG. 4 is a front elevational view thereof;

FIG. 5 is a top plan view thereof;

FIG. 6 is a rear elevational view thereof; and

FIG. 7 is a bottom plan view thereof.

I claim:

The ornamental design for a miniature tramway car and platform therefor, as shown and described.
